BROODER

John E. Schlottmann, Kenedy, Tex.

Application June 24, 1938, Serial No. 215,679

2 Claims. (Cl. 119—34)

This invention relates to certain new and useful improvements in brooders for chicks, and the primary object of the present invention is to provide a brooder having a novel arrangement of heating means, hover and runway.

More particularly, the present invention contemplates the provision of a brooder having hot water heating means, and wherein the hot water heating coil is so located as to function with maximum efficiency and to permit the supply and return water pipes thereof to be readily run under ground to avoid undue loss of heat and sudden temperature change in the brooder.

Other objects and features of the present invention will become apparent from the following description when considered in connection with the accompanying drawing, and the invention consists in the novel form, combination and arrangement of parts hereinafter more fully described, shown in said accompanying drawing and claimed.

In the drawing:

Figure 1 is a vertical sectional view of a brooder constructed in accordance with the present invention; and

Figure 2 is a horizontal section taken substantially on line 2—2 of Figure 1, with parts broken away and in section.

Referring in detail to the drawing, the present invention consists of a suitable shed or enclosure including front wall 5, rear wall 6, side walls 7 and roof 8, the enclosure being built upon the ground 9 and preferably having suitable windows 10 in the front wall 5 thereof.

In accordance with the present invention, the ground 9 is recessed as at 11 along one wall of the enclosure (preferably along the rear wall 6) to provide an air chamber below the surface of the ground. Arranged in this chamber or recess 11 is a hot water heating coil 12 embedded in sand and having suitable thermostatically controlled valve means 13 for controlling the flow of hot water therethrough and maintaining a uniform temperature within the brooder. As the heating coil 12 is arranged below the surface of the ground in the recess or chamber 11, its supply pipe 14 and return pipe 15 may be readily extended under ground to the boiler or hot water heater which supplies hot water to the heating coil, even though said boiler or heater may be located at a remote point from the brooder. In this way, there is little loss of heat and no danger of sudden change of temperature in the brooder as long as a constant supply of hot water is maintained. The major portion of the top of

recess or air chamber 11 is closed by a metallic plate 16 arranged flush with the level of the ground 9 within the enclosure, said plate terminating in an upturned flange 17 in spaced relation to the adjacent wall 6 of the enclosure. In this way, a flue 18 is defined between the flange 17 and wall 6 of the enclosure for the passage of air to chamber 11 and for flow of air heated by the coil or heater 12 from chamber or recess 11 to the interior of the enclosure above the floor of the latter. The top of this flue is covered by a porous relatively strong sheet of fabric 19 which permits the free passage of air to and from the chamber or recess 11 while preventing the chicks from entering said flue 18 and recess 11.

A layer, preferably about three inches in depth, of sand 20 is provided on the ground surface and the plate 16 within the enclosure to form the floor of the brooder, and disposed adjacent wall 6 but in spaced relation to and above the floor thus formed is a flat wall 21 extending from the wall 6 of the enclosure to a point adjacent but spaced from the opposed wall 5 and inclined downwardly toward the latter so as to provide between said wall 21 and the floor of the enclosure a hover chamber 22. The warm air passing from the air chamber 11 thus flows directly into the hover chamber 22 for providing the necessary warmth for the chicks in a generally well known manner and for a generally well known purpose. A curtain of fabric 23 is suspended from the lower forward edge of wall 21 toward the floor of the enclosure so as to permit the passage of the chicks into the hover chamber although minimizing the escape of warm air therefrom into the portion of the enclosure above the wall 21 and forwardly of the latter. It will be noted that the forward edge of wall 21 is sufficiently close to the floor of the enclosure to permit the chicks to readily have access to the top of said wall 21 so that the latter will form a suitable runway on which the chicks may walk and move about for obtaining the necessary exercise. This wall 21 is preferably hinged to wall 6 so that it may be swung upwardly as indicated in Figure 1, and it consists of a laminated member including a top asbestos layer or sheet 24, an intermediate layer of wool 25 and a bottom sheet or layer of aluminum 26. As the bottom aluminum sheet 26 is a good conductor of heat, it will serve to cause a very uniform distribution of heat throughout the top of the hover chamber 22. The top layer 24 of asbestos will protect the feet of the chicks from excessive

heat. The top of the wall 21 is provided with a series of small openings 27 through which the chicks may pass from the hover chamber 22 into the interior of the enclosure. The side walls 7 of the enclosure are provided with windows 10 and doors 28, and the roof 8 is provided with a series of small openings 29 through which the chicks may pass from the interior of the enclosure into the hover chamber 22. The side walls 7 and roof 8 are provided with insulation 30 and 31 respectively, and the entire enclosure is provided with a floor 32.

heat being transmitted thereto when the chicks are on the runway formed by the wall 21.

With the use of a brooder constructed as described above, it will be readily apparent that there will be a minimum loss of heat and danger of sudden change of temperature in the brooder is eliminated. Moreover, the heating means removes no humidity from the air within the brooder and it is not necessary to humidify the air by use of water pans, sprinkling the ground or the like, the droppings of the chicks supplying all of the humidity necessary. It will be seen that the construction is simple, compact and efficient, being extremely easy and economical 15 to build or construct and affording a very efficient enclosure within which to raise chicks during the period immediately following hatching or incubation. Minor changes in the details illustrated and described are of course contemplated within 20 the spirit and scope of the invention as claimed.

What I claim as new is:

1. A brooder structure built upon the ground with a recess in the ground along one vertical wall of said brooder structure, a horizontal cover 25 for the major portion of the top of said recess flush with the ground surface and terminating adjacent but spaced from said vertical wall of the brooder structure to afford an air flue for passage of heated air from said recess into the 30 portion of the brooder structure above said cover, a layer of sand on the ground and on said cover, a hot water heating coil located in said recess for heating air in the latter for passage through said flue to the interior of the brooder above said 35 above said cover, a wall disposed above said

cover in spaced relation to and adjacent the latter and extending from said vertical wall in an inclined position, said last-named wall having a top layer of heat insulating material to afford a runway thereon and hover chamber thereunder, said flue opening directly into one end of said hover chamber.

2. A brooder structure built upon the ground with a recess in the ground along one vertical wall of said brooder structure, a horizontal cover 10 for the major portion of the top of said recess flush with the ground surface and terminating adjacent but spaced from said vertical wall of the brooder structure to afford an air flue for passage of heated air from said recess into the 15 portion of the brooder structure above said cover, a layer of sand on the ground and on said cover, a hot water heating coil located in said recess for heating air in the latter for passage through said flue to the interior of the brooder above said 20 cover, a wall disposed above said cover in spaced relation to and adjacent the latter and extending from said vertical wall in an inclined position, said last-named wall having a top layer of 25 heat insulating material to afford a runway thereon and hover chamber thereunder, said flue opening directly into one end of said hover chamber, a porous cover for the top of said flue 30 preventing passage of the chicks from the hover chamber to said recess, and feed and return pipes for said heating coil extending from a heater remote to the brooder structure and embedded in the ground.

JOHN E. SCHLOTTMANN. 35
